J. L. TURNER.
PEN POSITIONING DEVICE.
FILED AUG. 26, 1921.

UNITED STATES PATENT OFFICE.

JESSE L. TURNER, OF LITTLE ROCK, ARKANSAS.

PEN-POSITIONING DEVICE.

Application filed August 26, 1921. Serial No. 495,471.

To all whom it may concern:

Be it known that I, JESSE L. TURNER, a citizen of the United States, residing at Little Rock, in the county of Pulaski and State 5 of Arkansas, have invented certain new and useful Improvements in a Pen-Positioning Device; and I do hereby declare the following to be a full, clear, and exact description of the invention, such as will enable others 10 skilled in the art to which it appertains to make and use the same.

The object of the invention is to provide a simple and efficient means as an assistance in the teaching of hand writing by properly positioning the pen in the hand of the student to insure a proper movement and more particularly an arm movement as distinguished from a finger movement, and with this object in view the invention consists in a construction and arrangement of parts of which a preferred embodiment is shown in the accompanying drawing, wherein:

Figure 1 is a view of a pen positioning device applied to a pen holder and showing 25 the same in engagement with a hand.

Figure 2 is a detail view of the device detached.

Figure 3 is a plan view with the part shown in the position indicated in Figure 1. 30 Figure 4 is a rear view partly in section to show the means for holding the adjustable tongue in position.

Figure 5 is a blank from which the body portion of the device is formed.

35 The holding device consists essentially of a clip 10 for engaging the pen holder staff and a thumb clamp 11 for straddling the thumb of the operator's hand at about the middle joint thereof, a seat 12 being arranged above the thumb clamp for the reception of a transverse stem 13 designed to extend transversely under the palm of the hand and project beyond the back or outer edge of the hand sufficiently to prevent the operator from turning the hand over or tending to turn the palm upward.

The pen holder clip consists of ears 10^a extending in opposite directions from a strap 14 which is doubled or coiled upon itself to 50 form the seat 12 which is located beneath and slightly in rear of the clip, one tongue 15 of the thumb clamp being formed preferably integral with and extending from the side of said strap at the lower side of the seat. The other tongue 16 of the thumb clamp is adjustable with relation to the seat

and the tongue 15 and to this end is provided with an arm 17 extending through the seat and provided with a plurality of openings or perforations 18 for selective engagement by a point or projection 19 which may as shown be formed by means of a punch applied to the under side of the seat. The arrangement of the stem in the seat serves to prevent looseness or accidental disarrangement or disadjustment of the movable tongue of the thumb clamp, and the seat being formed by a coil of which the end is free is preferably of such resilience as to exert a clamping action on the stem and thus hold 60 the latter in proper position. The material of which the device is formed is preferably sufficiently pliable to adapt it to be bent to fit the object used in connection therewith, such as the pen holder, etc., but at the same 65 time has a sufficient amount of resilience to properly yield to exert a clamping action while retaining its general form. Aluminum is a suitable material for the purpose.

The effect of the device when applied to 70 the hand as indicated and as shown in the drawing is to hold the hand of the operator and the pen in the hand in the proper relation and position prescribed by the authorities on hand writing, and the thumb clamp 75 serves to embrace or clasp the joint of the thumb and owing to the feeling of security which the pupil has by reason of recognizing that the pen holder is safely held in the hand there is induced a relaxation of the 80 muscles of the arm and hand so that the task of teaching an arm movement in hand writing is very materially facilitated. As above indicated the turning of the hand tending to bring the palm upward or to the 85 side is prevented by the projected end of the stem which extends under the palm of the hand and at the same time the hand is held in the flat position which is prescribed 90 to insure a proper position of the pen holder 100 with relation to the surface which is to receive the writing.

It will further be observed that the device is of simple construction, and may readily be formed by stamping from sheet metal, of 105 for example about twenty gage, and may readily be applied to a pen holder staff and adapted by the simple adjustment of the movable tongue of the clamp to fit the thumb of the pupil so as to insure a proper position 110 in writing and overcome the prevalent tendency to finger movement whereas the pre-

ferred movement is that of the arm and which is ordinarily difficult to teach by reason of the fact that the majority of pupils feel that it is necessary to pinch or grasp the pen holder tightly and in so doing they cramp the muscles and produce a stiffness which renders the arm movement impossible. The security of feeling experienced by the student in using the holding device induces an immediate relaxation of muscles which predisposes him or her to the required freedom of arm movement.

Having thus described the invention, what I claim is:—

- 15 1. A pen holding device having means engageable with the thumb to prevent undue movement of the latter, means extending from the said means engageable by the palm of the hand to prevent disengagement of the first means from the thumb, and a staff-retaining means associated with said means.
- 20 2. A pen holding device having means engageable with the thumb to prevent undue movement thereof, a stem on said means and extending therefrom for engagement by the palm of the hand to prevent disengagement of the said means from the thumb, and a staff-retaining means extending from the said means over said stem to secure it in place.
- 30 3. A pen holding device having a staff engaging clip and a thumb clamp adapted for straddling engagement with the thumb

of the hand, the thumb clamp consisting of spaced tongues, one of which is movable toward and from the other.

4. A pen holding device having a staff engaging clip and a thumb clamp adapted for straddling engagement with the thumb of the hand, and a stem extending transversely from the thumb clamp for contact with the palm of the hand.

5. A pen holding device having a staff engaging clip and a thumb clamp adapted for straddling engagement with the thumb of the hand, a transversely open looped seat being arranged between the clip and thumb clamp for the reception of a transverse palm rest stem.

6. A pen holding device having a staff engaging clip and a thumb clamp adapted for straddling engagement with the thumb of the hand, a coiled seat being arranged between the said clip and clamp, one side of the thumb clamp consisting of a tongue having an arm extending adjustably through the seat, interlocking means for securing said tongue in its adjusted position, and a stem fitted in the seat for extension beneath the palm of the operator's hand.

In testimony whereof I affix my signature in presence of two witnesses.

JESSE L. TURNER.
